UNITED STATES PATENT OFFICE.

SAMUEL MCILVAINE, OF OAKWOOD, ONTARIO, ASSIGNOR TO CATHARINE MCILVAINE, OF TORONTO, CANADA.

GAS-GENERATOR.

SPECIFICATION forming part of Letters Patent No. 402,584, dated April 30, 1889.

Application filed February 14, 1888. Serial No. 263,967. (No model.)

To all whom it may concern:

Be it known that I, SAMUEL MCILVAINE, of Oakwood, in the Province of Ontario and Dominion of Canada, have invented a new and 5 Improved Retort-Vaporizer, of which the following is a full, clear, and exact description.

My invention relates to an improvement in vaporizers, and has for its object to provide an apparatus of simple and cheap construction capable of use in any household and manipulation by any person of ordinary judgment and experience.

The invention consists in the construction and combination of the several parts of the 15 apparatus, as will be hereinafter fully set forth, and pointed out in the claims.

Reference is to be had to the accompanying drawing, forming a part of this specification, which represents a central vertical section 20 through the improved generator.

In carrying out the invention a retort, 10, is constructed of cast-iron or fire-clay, preferably cylindrical in general contour, which is in practice so located in the combustion 25 chamber of a stove or furnace that its bottom is in close proximity to the fire or coals, so that the retort is heated to a due degree. The upper end of the retort is provided with an aperture, 11.

30 In the center of the retort at the bottom a conical depression, 12, is produced, the object thereof being to obtain greater heating-surface, and over the interior projection thus formed within the retort a funnel-shaped partition, 14, is suspended. The diameter of the funnel is greater than that of the conical projection, and the said funnel is so hung as that the upper end or neck will be located centrally in the aperture 11 and flush with the upper edge 35 of the retort, and the lower or cap portion will be spaced from the bottom of said retort. By means of this funnel-shaped partition and the projection the retort is divided into two chambers, 15 and 16, and all parts 40 of the interior are but slightly removed from a heating-surface. A cylinder, 17, is bolted upon the retort over the aperture therein, the joints being made tight by an asbestos packing, and at the upper end the said cylinder 45 is provided with a detachable cover, 18, held in position by a suitable clamp, 19.

An annular cylinder, 20, for containing water surrounds the vertical cylinder 17, and in practice rests flat on a stove or furnace top, 21, while the retort 10 is located within the 55 fire-box of the stove or furnace. A tube, 22, is passed from the boiler 20 into the cylinder 17 and vertically downward within the cylinder to a connection with the funnel 14 and into the retort. From the said tube 22 outside the cylinder another tube, 23, is projected upward, which connects with a tank, 30, adapted to contain crude oil. The pipes 22 and 23 are each provided with a valve, 24 and 25.

From the cylinder 17 an outlet-pipe, 26, is projected, connected to any suitable gas-tank. The receptacle 20 is provided with a water-inlet, a safety-valve, and a discharge-faucet.

In operation the retort is filled with about 70 four parts fine charcoal or coke, preferably the former, and one part of iron scraps or trimmings well mixed together, the carbon monoxide being decreased by increasing the proportion of iron. The boiler 20 is half-filled with water and the tank 30 with crude oil. When the retort is red-hot and steam is generated in the boiler, the oil-valve being closed and the steam-valve open, the steam will thereupon enter the funnel-chamber 15 75 and become highly superheated and partly decomposed by contact with the hot iron and charcoal and converted into hydrogen and carbon monoxide, but considerably more hydrogen gas, the proportion of hydrogen being 80 increased by increasing the proportion of iron. These gases and superheated steam not decomposed now pass under the funnel and up through the mass of red-hot iron and charcoal or coke in the chamber 16, whereupon, rising upward and passing into the cylinder 17, the gases find an exit through the pipe 26 into a suitable gas-holder, as in water-gas hydrogen. When the gas-holder becomes about one third full the steam is shut 90 off and the oil is turned on in proper quantities, regulated by the valve 24. The oil, passing through the chambers 15 and 16, is decomposed and converted into an excellent illuminating-vapor, which upon entering the 95 gas-holder mixes with the hydrogen, producing a gas ready for use without further puri-

fication. The hydrogen is more or less carbureted, according to the proportion of oil employed.

The iron scrap or trimmings serve to keep the charcoal or coke hot as the steam or oil circulates through it. The iron also creates more hydrogen, as it takes up the oxygen from the water and prevents a surplus uniting with the carbon.

10 Having thus described my invention, what I claim as new, and desire to secure by Letters Patent, is—

15 1. In a retort-vaporizer, the combination of the following parts: a retort having an open top and a central bottom elevation, a vertical cylinder set on said retort and having a

gas-exit pipe, and a steam and oil pipe passing down through the cylinder and connecting with a funnel which partly incloses the aforesaid elevation, all as shown and described. 20

2. In a retort-vaporizer, the combination, with a vertical cylinder and a retort below the same, of an annular steam-generator surrounding the cylinder, a steam-pipe connecting with the generator, and an oil-pipe joined 25 with said steam-pipe and extending down through the cylinder, and a funnel connected with said pipe, as shown and described.

SAMUEL McILVAINE.
